UNITED STATES PATENT OFFICE.

FRED A. FORD, OF NEW YORK, N. Y., ASSIGNOR TO J. W. GILLIS CO., OF ROCHESTER, NEW YORK, A CORPORATION OF NEW YORK.

TELEPHONE STAND.

Application filed June 2, 1926. Serial No. 113,257.

The object of this invention is to provide a new and improved type of telephone stand.

This and other objects of this invention 5 will be fully illustrated in the drawings described in the specification and pointed out in the claims at the end thereof.

In the accompanying drawing:

Figure 1 is a front elevation of the telephone stand with the revolving screen turned to expose the telephone.

Figure 2 is a top plan view of the telephone stand without the telephone.

Figure 3 is a horizontal section thru the stand, the section being taken on the line 3^x—3^x of Figure 1.

Figure 4 is a partial horizontal section and top plan view of the stand, the section being taken on the line 4^x—4^x of Figure 1.

Figure 5 is a vertical section of the stand with the revolving screen partly broken away, the section being taken on the line 5^x—5^x of Figure 2.

In the several figures of the drawing like 25 reference numerals indicate like parts.

The telephone stand forming the subject matter of this invention is provided with a revoluble screen that can be turned to either expose or conceal the telephone supported 30 thereon.

As illustrated in the figures the stand comprises the sub-base 1 having the pivot post 2 suitably fastened or anchored centrally thereof. In the top of this sub-base 35 are located a series of three rollers 3, 3 which are mounted to rotate in suitable cradles that are mortised and fastened into the top of the sub-base with a portion of the roller projecting slightly above the level of the 40 base.

Into the bottom of the sub-base are fastened or anchored a pair of weights 4, 4 that serve to load the base to make it heavy and give it a firm footing. A cloth covering or 45 pad 5 is glued to the bottom of the sub-base to cover up the weights 4, 4 and will provide the base with a finish that when placed on a table will not scratch its surface.

The portion of the central post 2 projecting 50 from the sub-base 1 is enlarged in diameter for a short distance. This enlarged portion of the central post provides the pivot for the turntable 6 which is placed on top of the sub-base 1 and is supported by the rollers 3, 3. This turntable slightly

overhangs the sub-base 1 on one side thereof and to this overhanging portion of the turntable is fastened the vertical screen or partition 7. This partition projects upwardly from the base and in the form illustrated is built up in three straight sections that are placed angularly with relation to one another in the form of half of a hexagon. The top of these sections are finished off in a pleasing design.

Above the turntable and on top of the central post 2 is supported the base 8 proper. A shallow circular pocket 9 is provided in the bottom of this base to receive the upper end of the central post 2 and screws 10, 10 60 are threaded into the end of the post located in this pocket from the top of the base to firmly fasten the base to the post and hold it stationary with the sub-base. The telephone is placed on top of the base and supported thereon. When it is desired to use the 'phone the screen is turned to expose the 'phone as illustrated in Figure 1.

The turntable is provided with an anti-friction roller 11 similar to the rollers 3 provided in the sub-base 1. This roller is supported in the top of the turntable and projects slightly above it to engage the under side of the base 8. The contact which the roller 11 makes with the under side of the 80 base 8 is at a point diametrically opposite to the center of the screen that is supported on the turntable. In this way the weight of this screen which has a tendency to tilt the turntable will not cause undue frictional 85 contact between the turntable and the base as a constant rolling contact is maintained between the turntable and the sub-base on one side and the base proper on the other side.

The screen can thus be freely rotated around the telephone supported on the base 8 of the stand so as to either conceal the telephone behind it or expose it when it is to be used.

A finishing pad 12 is attached to the top of the base to conceal the screws 10, 10 that fasten the base 8 to the post 2 and a design may be worked into this cover to give the base a pleasing appearance.

While a three sided screen is shown mounted on the turntable and adapted to turn thereon, it is obvious that the screen may be in the form of a hexagon or a whole cylinder or two cylinders, etc., hinged 110

together, or in the form of any other barrier that may be desired.

I claim:

1. A telephone stand comprising a sub-base, a post mounted centrally of said sub-base, antifriction rollers mounted in the top of said base, a base supported on top of said post and a turntable located between said base and said sub-base and adapted to rotate around said post as a center and on top of said antifriction rollers, a decorative screen carried on the periphery of said turntable and adapted to rotate therewith concentric to said base and sub-base, said decorative screen projecting above said base and partially encircling it.
2. A telephone stand comprising a stationary sub-base, a fixed post mounted centrally of said sub-base, a turntable mounted to rotate on said sub-base, a stationary supporting base mounted on said post above said turntable and a screen open at one side carried by said turntable and rotating therewith concentric to said stationary supporting base and said sub-base to either expose or conceal a telephone placed on said supporting base.
3. A telephone stand comprising a sub-base, a pivot post mounted centrally of said sub-base, antifriction rollers mounted in the

top of said sub-base, a turntable mounted to rotate on said pivot post and supported on said antifriction rollers, a screen fastened to one side of said turntable, a stationary base supported above said turntable, an antifriction roller mounted on top of said turntable and engaging the under side of said stationary base at a point diametrically opposite to said screen.

4. A telephone stand comprising a stationary sub-base, antifriction rollers mounted in the top of said sub-base and slightly projecting above it, a fixed post mounted centrally of said sub-base, a turntable mounted to rotate on top of said sub-base and supported by said antifriction rollers, a decorative screen mounted on a portion of the periphery of said turntable and projecting upwardly therefrom, a stationary supporting base above said turntable and mounted on said fixed post, said decorative screen projecting above said supporting base and encircling a portion of the periphery thereof, and means provided on said turntable at a point diametrically opposite to said decorative screen to prevent said turntable from tilting.

In testimony whereof I affix my signature.

FRED A. FORD.
